CLAIM

The ornamental design for an electrical radiant heater,
substantially as shown and described.

DESCRIPTION

FIG. 1 is a front elevational view of an electrical radiant
heater, showing my new design;

FIG. 2 is a rear elevational view thereof;

FIG. 3 is a left side elevational view, the right side being
a mirror image thereof;

FIG. 4 is a top plan view thereof.

The bottom surface of the electrical radiant heater is
substantially planar and unornamented.

FIG 1

FIG 2

FIG 3

FIG 4
